SCREW CAP REMOVER

James P. McCready, New York, N. Y.

Application September 10, 1934, Serial No. 743,475

1 Claim. (Cl. 81—3.1)

This invention is a device for facilitating the removal of screw caps from jars, and particularly for facilitating the removal of the threaded cap of "Mason" jars and the like.

5 An object of the invention is to provide a simple and easily operated form of wrench particularly adapted for the purpose above mentioned, and which also includes as an integral part thereof a can opener and a crimped bottle cap remover.

10 The invention, together with its objects and advantages, will be best understood from a study of the following description taken in connection with the accompanying drawings wherein:

15 Figure 1 is an upper side view in elevation of the improved form of wrench.

Figure 2 is a perspective view thereof.

Figure 3 is a perspective view of the movable jaw of the wrench.

20 Figure 4 is a perspective view of a cam equipped lever.

Figure 5 is an end elevational view of the wrench showing the same applied to a screw cap.

Figure 6 is a view similar to Figure 1 illustrating a slightly modified form of the invention.

25 Figure 7 is a perspective view of an end portion of a shank forming part of the second form of the invention.

Figure 8 is a perspective view of the removable jaw and associated parts.

30 Referring to the drawings by reference numerals, it will be seen that in both forms thereof the invention comprehends the provision of a screw cap remover in the form of a wrench and including a flat elongated shank 10 provided at one end with a handle 11.

In the form of the invention shown in Figures 1 to 5 inclusive the shank 10 at the free end thereof has integral therewith a laterally extending jaw 12 that is in a plane offset to the plane 40 of the shank 10 and is connected with the front of the shank by a narrow web 13 that extends at right angles to the plane of the shank and is integral with the shank 10 and the jaw 12. The jaw 12 is slightly tapered and adjacent its free 45 end merges into a flange 14 paralleling the flange 13 and which connects the jaw 12 with a bottle cap remover 15. On its gripping face the jaw 12 is provided with teeth 16.

In both forms of the invention, the shank 10 on 50 the back thereof is toothed as indicated at 17. Also, in both forms of the invention, a slide 18 is mounted upon the shank, and may be of any preferred construction, the slide preferably being, and as shown, formed from a single blank and 55 comprising spaced parallel side plates 19 which,

at one corner, are connected together by a substantially U-shaped tooth 20 and at a relatively opposite corner and for a considerable part of the length thereof are connected by an integral toothed jaw 21 (see Figure 3). The tooth 20 of 5 the slide 19 matches the teeth 17 on the shank, whereby to hold the slide 19 in the required adjusted position. The jaw 21 is toothed to match the teeth of the jaw 12 for clamping between said jaws the screw cap of the jar. 10

A cam 22 formed integrally one end of a handle or lever 23 is pivotally connected to the slide 19 as at 24 at the end of the slide equipped with the jaw 21.

When the movable jaw, that is, the jaw 21 15 provided on the slide 19 is in locked position, the parts assume the position shown, as for example in Figure 1, the shank 17 being held between the tooth 20 and the cam 22. When it is required to adjust the movable jaw 21, the lever 20 23 is rotated in a direction outwardly or away from the shank 10 whereby provision is made for releasing the tooth 20 and permitting the slide to be moved along the shank 10 to adjust the jaw 21 to accommodate the particular jar cap or work, 25 after which the slide 18 and jaw 21 associated therewith are made secure by pressing the lever 23 inwardly to the position shown in Figure 1 so that cam 22 and tooth 20 thus engage with the shank 10 in a manner to lock the slide 19 and 30 the jaw 21 carried thereby.

By having the jaw 12 offset from and parallel to the plane of the shank 10, and the bottle cap remover 15 arranged substantially coplanar with the shank 10 it will be seen that the shank 35 10 and the bottle cap remover 15 rest on top of the screw cap 24 that is to be removed from the jar 25 and with the toothed face of the jaw 12 engaging the periphery of the cap 24, the cap 24 thus provides a support for the jaw 40 equipped end of the shank 10 permitting quicker action on the part of the operator in adjusting the jaw 21 and the clamping thereof at the required adjusted position.

The form of the invention shown in Figures 45 6 to 8 inclusive is used in substantially the same manner as is the form of the invention shown in Figures 1 to 5 inclusive. However, in the second form of the invention, that is, in the form of the invention shown in Figures 6 to 8 inclusive, instead of having the fixed jaw integral with the shank, said jaw indicated by the reference numeral 12' is integral with an attaching plate 26 in the same manner as the jaw 12 is integral with the shank 10. Also, the bottle cap remover 50 55

15' is integral with the jaw 12' in the same manner as is the bottle cap remover 15 integral with jaw 12. In the modified form of the invention, 5 the plate 26 is adapted to be secured to the free end of the shank 10' by rivets or any other suitable fastening means 27, and integral with the plate 26 at the edge thereof opposite to the jaw 12' is a can opener blade 28.

What is claimed is:

- 10 A wrench of the class described comprising an elongated shank having teeth at its rear side, a stationary jaw connected at one end to the front side of the shank, said jaw having a portion in a plane offset from the plane of the shank and 15 having an inwardly extending projection at the outer end thereof, lying substantially in the

same plane as the shank, the offset portion having teeth on its inner side thereof, a movable jaw of elongated form and of channel-shape in cross section having an opening at its bight adjacent one end thereof through which the shank passes, said end of the movable jaw having a tooth thereon for engaging the teeth of the shank and the bight of the movable jaw between the opening and the other end having teeth thereon to cooperate with the teeth on the first-mentioned jaw and a handle pivoted at said other end of the jaw between the flanges of the channel and provided with a cam at its pivoted end for engaging the front edge of the shank. 5 10 15

JAMES P. McCREADY.
